CLAIM

The ornamental design for a luggage rack, as shown and described.

DESCRIPTION

FIG. 1 shows a perspective view of the luggage rack mounted on a motorcycle.

FIG. 2 shows a side view of the luggage rack mounted to the backrest of a motorcycle.

FIG. 3 shows a top view of the luggage rack with the panels extended.

FIG. 4 shows a bottom view of the luggage rack with the panels collapsed.

FIG. 5 shows a rear view of the luggage rack with the panels extended; and,

FIG. 6 shows a front view of the luggage rack with the panels extended.

The broken lines represent environmental subject matter and form no part of the claimed design.
